METHOD OF PREPARING COLOR PRINT PLATES

Walter S. Marx, Jr., Park Ridge, Ill., assignor to
 Printing Arts Research Laboratories, Inc.,
 Santa Barbara, Calif., a corporation of Dela-
 ware

Application November 16, 1939, Serial No. 304,735

13 Claims. (Cl. 95—5.1)

This invention relates to a new and improved method of preparing color printing plates. While the invention relates particularly to the preparation of multi-color printing plates, certain aspects of the invention apply to plates for line printing in black, and half-tone printing in color.

One of the objects of this invention is to provide a new and improved method of preparing plates for printing cartoons or colored comic supplements in multicolor, so as to provide a simple and efficient method for newspaper work.

Another object of this invention is to provide a new and improved method of preparing plates for printing in multicolor, so as to eliminate the necessity of using skilled operators for securing correct color rendering and blending.

A further object of the invention is to provide an improvement in efficiency and results over the current methods of preparing color-printing plates, and more specifically over the method commonly known as the "Benday process."

Other objects of this invention are set forth in the following description and drawing, which illustrate certain preferred embodiments.

In the drawing:

Fig. 1 illustrates diagrammatically certain apparatus which may be used in the carrying out of the method according to the present invention, and

Fig. 2 is also a diagrammatic view of certain alternative apparatus which can be employed to a like end.

The preferred embodiment of the present invention will be described in connection with the preparation of colored comic supplements and cartoons from a black-and-white pen drawing such as is usually furnished to the engraver in existing methods, although it is to be understood that the invention has other applications as will hereinafter be referred to.

According to the present invention such a black-and-white pen drawing is first photographed without a screen so as to produce a negative from which is prepared a line positive on any suitable light-permeable or transparent material and such as glass or Celluloid, the size of such line positive or transparency being of the same size as the printing plates finally to be prepared, as will hereinafter appear.

If preferred, the positive transparency may be lightly printed, that is to say, the black lines thereon are fainter than those in the original drawing, thus making it possible to form a screen or half-tone dot formation of these lines in the color separation negatives subsequently to be prepared from the line positive, as will herein-after be described.

Next the surface of the line transparency is preferably prepared so as to render it properly

receptive of coloring material, and this may comprise applying thereto a solution consisting of:

	Parts
Water	88
Egg albumen	8
Ammonium hydroxide	4

With the surface of the positive transparency in proper condition, the transparency is colored by local applications of various transparent coloring materials so as to produce the desired color scheme, the black lines which have been produced being used as a guide for applying the said colors.

15 Three different color separation negatives are next made from the colored transparency and for this purpose the apparatus illustrated in either Fig. 1 or 2 is utilized.

20 Referring first of all to Fig. 1, C indicates an orthodox process camera and L the lens thereof, whilst B indicates a copy board disposed in front of the lens and on which is mounted in any suitable way a sheet of white paper P. A suitable sensitized negative element N is mounted within the camera, and in front thereof and in effectual contact therewith is placed the colored transparency T, preferably with its colored surface facing the sensitized surface of the negative N. In front of the transparency T is positioned the half-tone screen S, whilst on or adjacent the lens L is positioned the appropriate color separation filter F.

25 On exposure the light transmitted from the white paper P through the lens L is used to form an image of the transparency T on the negative element N, said light being first filtered by the filter F and then broken up into a half-tone pattern by the screen S. Thus the resulting negative is a color separation half-tone and may be printed directly on metal and etched and processed in the usual way to provide one plate of the multicolor series.

30 A similar negative is made in the same way for each of the remaining colors, from which the remaining plates, to complete the multicolor series, can be produced, the appropriate color separation filter F of course being placed in position prior to the exposure of each negative. In addition, the necessary black printing plate must be provided and this can be conveniently obtained from the negative previously used in making the positive transparency T.

35 Alternatively, the color separation half-tone negatives can be obtained in accordance with the invention with the apparatus of Fig. 2. In this case, instead of the camera C and light source comprising the white paper P there is provided the projection printing apparatus A having the lamp A' and lens L, and which latter may carry the appropriate color separation filter F as before.

In front of and below the lens is placed the half-tone screen S; below this, and preferably spaced therefrom, such as by bars X, is located the colored transparency T which is in effectual contact with the sensitized negative element N, as before, the transparency being preferably arranged so that its colored surface faces the emulsion or sensitized surface of the negative element N.

It is to be particularly noted that in the methods described with reference to both Fig. 1 and Fig. 2 the color separation negatives are obtained by means of transmitted light as opposed to reflected light and with the colored transparency in effectual contact with the said negatives.

In this connection it should be pointed out that the value of transmitted light in color separation procedure is much more efficient than the value of reflected light as used in common practice for the following reasons: (a) Reflected light is degraded by secondary surface reflection and inter-reflection; (b) Current lens construction is such that various wave lengths of light are not accurately focused in one plane; (c) The types of glass commonly used in color corrective lenses is such that the color corrective efficiency is far from perfect; and (d) Incident light is such that it may be degraded by surrounding foreign reflections and by lights which may by accident strike the color drawing in use.

As opposed to the above disadvantages: (a) Transmitted light cannot be degraded where the color transparency is in effectual contact with the negative element; (b) All wave lengths of light are at once accurately in one plane without the use of a lens and without the necessity for focusing; and (c) According to the Grotthous-Drapier law, only light which is absorbed can have an effect; thus by absorbing actinic light first through the color separation filter and second through the color transparency, greater color separation distinction is achieved than if said light were first reflected from colored art and then pass through the separation filter, as is the procedure in common practice.

From the above it will be appreciated that by preparing the color transparency T on a light-permeable material, mounting said transparency in effectual contact with the negative element N and exposing the latter so arranged to a source of transmitted light, all of the advantages above mentioned are realized by the present method.

A further advantage of the present method consists in that in the event of breakage of a color separation negative careful refocusing is no longer necessary, because by the present method the original color transparency by being mounted in effectual contact with a new negative element will, of course, provide a color separation negative of the exact size of the one broken.

Further, the least expensive method for color printing which has heretofore been accepted is the "Ben Day process." The prior process, however, does not provide fine, delicate and numerous shadings and gradations of color, which must be produced by hand. On the contrary, by the present method such fine, delicate and numerous shadings are made photo-automatically.

The efficiency of this invention may be further greatly improved by the addition, to the transparent coloring materials used to color the positive transparency T, of an ultra-violet absorbent material and by subjecting the color

separation negatives to an auxiliary exposure in the presence of ultra-violet light.

For instance, if the colored areas of the positive transparency T contain an efficient absorbent of ultra-violet light, for example:

Distilled water	c. c.	1000
Quinine bisulfate	grams	80
Sulfuric acid, C. P.	c. c.	10
Egg albumen, C. P.	grams	15

these areas will prevent the penetration of ultra-violet light. And conversely, the uncolored areas, namely backgrounds, highlights, etc., will transmit ultra-violet light. Thus if, after the normal color separation exposure, as hereinbefore described, is completed, the screen is removed and the color separation negatives are subjected to an additional exposure in the presence of ultra-violet light, the screen pattern or dots will be obliterated in those sections of the negatives corresponding to the uncolored sections of the positive transparency T. Those sections of the negatives directly behind the colored sections of the positive transparency will not be affected by the ultra-violet light, since that light is effectually absorbed before it reaches the negative, by the ultra-violet absorbent included in the colored sections.

The advantage of thus obliterating screen pattern in the high-light areas or sections consists in eliminating the hand labor usually required to "opaque" these areas or sections on the screened negatives so that subsequently they will print upon the metal as areas which are entirely free of dot pattern, i. e., as perfectly white or uncolored areas.

It is understood that while the method according to the present invention has been more particularly described in connection with the production of preparing plates for printing cartoons or comic supplements in multicolor, it has other applications and such, for example, as the reproduction of photographs which may be similarly reproduced by preparing a colored transparent positive thereof. This transparency may be made either by hand-coloring or by direct photographic means, and such as, for instance, by what is currently commonly known as a "Kodachrome" transparency. In this case, there being no previously made black-printing negative, all three, four or more color separation negatives are made while the transparency is in contact with the negative inside the camera.

Further and finally, whilst the present invention relates particularly to the printing of colored cartons, colored supplements and the like, by means of high speed rotary newspaper presses, it is also applicable to the well known color printing processes, using two, three, four or more colors, and to fine screen reproductions.

I claim:

1. In the art of preparing printing plates for multicolor printing of matter, said matter containing black lines, those steps which consist in photographically printing a black-and-white positive of said matter upon a light-permeable material, preparing a color scheme with transparent colors upon said positive, and preparing therefrom half-tone screen separation negatives by contact photographic printing.

2. In the art of preparing printing plates for multicolor printing of matter, said matter containing black lines, those steps which consist in photographically preparing a negative of said matter, photographically printing a black-and-

white positive upon a light-permeable material from said negative, coloring said positive transparency with transparent colors, and preparing therefrom half-tone screen separation negatives by contact photographic printing.

3. In the art of preparing printing plates for multicolor printing of matter, said matter containing black lines, those steps which consist in photographically preparing a negative of said matter, photographically printing a black-and-white positive upon a light-permeable material from said negative, coloring said positive transparency with transparent colors, preparing therefrom half-tone screen separation negatives by contact photographic printing, and preparing the black printing plate from the negative used originally in preparing the black-and-white positive.

4. In the art of preparing printing plates for multicolor printing of matter, said matter containing black lines, those steps which consist in photographically printing a black-and-white positive of said matter upon a light-permeable material, coloring said positive with transparent colors, placing said positive in effectual contact with a sensitized negative element and then exposing said negative to a source of transmitted light with a half-tone screen and a color separation filter interposed between said positive and said source of transmitted light.

5. In the art of preparing printing plates for multicolor printing of matter, said matter containing black lines, those steps which consist in photographically printing a black-and-white positive of said matter upon a light-permeable material, coloring said positive with transparent colors, placing said positive in effectual contact with a sensitized negative element inside a camera and then exposing said negative to a source of transmitted light with a half-tone screen and a color separation filter interposed between said positive and said source of transmitted light.

6. In the art of preparing printing plates for multicolor printing of matter, said matter containing black lines, those steps which consist in photographically printing a black-and-white positive of said matter upon a light-permeable material, preparing a transparent color scheme thereon, and preparing color separation half-tone negatives from said color transparency by mounting said transparency in effectual contact with a photo-sensitive negative element inside a camera.

7. In the art of preparing printing plates for multicolor printing of matter, said matter containing black lines, those steps which consist in photographically printing a black-and-white positive of said matter upon a light-permeable material, preparing a transparent color scheme thereon, preparing color separation half-tone negatives from said color transparency by mounting said transparency in effectual contact with a photo-sensitive negative element inside a camera, and repeating the last mentioned step once for each color separation negative.

8. In the art of preparing printing plates for multicolor printing of matter, said matter containing black lines, those steps which consist in photographically preparing a negative of said matter, photographically printing a black-and-white positive upon a light-permeable material from said negative, coloring said positive with transparent coloring material, preparing color separation half-tone negatives from said color transparency by mounting said transparency in

effectual contact with a photo-sensitive negative element inside a camera, repeating the last mentioned step once for each color separation negative, and preparing the black printing plate from the negative used originally in preparing the black-and-white positive.

9. In the art of preparing printing plates for multicolor printing of matter, said matter containing black lines, those steps which consist in photographically printing a black-and-white positive of said matter upon a light-permeable material, coloring said positive with transparent coloring material, successively placing said positive in effectual contact with a plurality of sensitized negative elements and then exposing it whilst in contact with each of said negative elements to a source of transmitted light and with a half-tone screen and an appropriate color separation filter interposed between said positive and the said source of light whereby to produce a plurality of half-tone color separation negatives, one for each color.

10. In the art of preparing printing plates for multicolor printing of matter, those steps which consist in mounting a colored transparency of said matter, the colors of which transparency include an absorbent of ultra-violet light, in effectual contact with a photo-sensitive element, preparing a color separation half-tone negative from said color transparency in said position by means of transmitted light and then re-exposing said negative in the presence of ultra-violet light only.

11. In the art of preparing printing plates for multicolor printing of matter, those steps which consist in photographically printing a black-and-white positive of said matter upon a light-permeable material, preparing upon said positive a color scheme with transparent colors having included therein an absorbent of ultra-violet light, preparing from said positive a half-tone screen separation negative by contact photographic printing and re-exposing said negative in the presence of ultra-violet light only.

12. In the art of preparing printing plates for multicolor printing of matter, those steps which consist in producing the desired color scheme upon a positive transparency of said matter in transparent colors containing an absorbent of ultra-violet light, producing half-tone separation negatives from said colored transparency with the aid of transmitted light, re-exposing said negatives in the presence of ultra-violet light only and utilizing said negatives for preparing the printing plates corresponding to the respective colors.

13. In the art of preparing printing plates for multicolor printing of matter, said matter containing black lines, those steps which consist in photographically printing a black-and-white positive of said matter upon a light-permeable material, coloring said positive with coloring matter including an absorbent of ultra-violet light, placing said positive in effectual contact with a sensitized negative element, exposing said

negative to a source of transmitted light with a half-tone screen and a color separation filter interposed between said positive and said source of transmitted light, removing the screen and filter and re-exposing the negative element in the presence of ultra-violet light only whereby to efface screen pattern in the areas of said negative corresponding to the high-light sections of said matter.
